FOUNTAIN RECEPTACLE

Prosper Powell, Norfolk, Va.

Application October 1, 1947, Serial No. 777,258

7 Claims. (Cl. 137—21)

1

My invention consists in new and useful improvements in a fountain receptacle for cleansing and retaining ice cream dippers, spoons, and the like in the operation of a soda fountain and has for its object to provide such a device which is simple in construction, convenient and sanitary in use and one which may be readily removed from the fountain well or syrup rail for purposes of cleaning and sterilization.

Sanitary laws require that equipment of this character be frequently removed and thoroughly cleaned and sterilized. Heretofore, considerable difficulty and inconvenience have been encountered by soda fountain operators in disconnecting the running water and drainage conduits when it became necessary to remove a receptacle from the fountain well, which often necessitated reaching under the fountain and generally disturbing the fountain procedure whenever removal of the receptacle was required.

With my improved receptacle, the running water supply and the drain are so connected and arranged in connection with the means for suspending the receptacle in the fountain well that the device may be simply lifted from the well and the water supply and drain readily disconnected from a point above the fountain deck.

A further object of my invention is to provide a means for adjustably suspending the receptacle in a fountain well to compensate for variations in the angle of inclination of the fountain deck whereby the receptacle is adaptable to various conventional soda fountains.

Still another object of my invention is to provide in a fountain receptacle, a removable partition whereby the receptacle may be divided to segregate different sizes of dippers and spoons.

With the above and other objects in view which will appear as the description proceeds, my invention consists in the novel features herein set forth, illustrated in the accompanying drawings and more particularly pointed out in the appended claims.

Referring to the drawings in which numerals of like character designate similar parts throughout the several views:

Fig. 1 is a perspective view of my improved fountain receptacle;

Fig. 2 is a fragmentary plan view partly in section, showing relationship of the adjustable suspending flange to the front wall of the receptacle;

Fig. 3 is a vertical longitudinal section on line 3—3 of Fig. 4; and

Fig. 4 is a transverse sectional view taken on line 4—4 of Fig. 3.

In the form shown in the drawings, the body of the receptacle is rectangular in shape, having a front wall 5, a rear wall 6, and two end walls 7 and 8. A bottom 9, preferably of the false bottom type, is secured to all four walls at a predetermined level above their lower extremities, by means of downturned flanges which are brazed, welded or otherwise secured to the walls of the receptacle as will be seen from Figs. 3 and 4.

A pair of outwardly directed right angle brackets 10 and 11 are secured to the front and rear walls 5 and 6 respectively, of the receptacle for suspending the latter in a syrup rail or suitable well located in the deck of a soda fountain (not shown). The front bracket 10 is adjustably mounted in vertical sliding relation to the upper portion of the front wall 5, by means of oppositely disposed guide angles 12, fixed to the front corners of the receptacle. The guide angles 12 are rigidly secured to respective side walls 7—8, with the front leg of each angle spaced forwardly from the front wall 5, a sufficient distance to slidably accommodate the longitudinal extremities 25 of the vertical leg 13 of the suspending bracket 10. The front legs of brackets 12 are provided with vertically extending slots 14 which cooperate with adjusting nuts and bolts 15, carried by the vertical leg 13 of the forward bracket 10, whereby said bracket is vertically adjustable on the front wall 5 of the receptacle. The horizontal leg of the angle bracket 10 is recessed at the inner edges of its longitudinal extremities as at 16 to accommodate the guide angles 12 and permit the vertical movement of the bracket.

The rear angle bracket 11 overlies the inner face of the rear wall 6 adjacent its upper edge and its vertical leg 17 is provided with vertical slots 18 for the reception of screws 19 carried by the rear wall 6 adjacent its upper edge, whereby the bracket 11 may be readily lifted from the wall 6 for the purpose hereinafter set forth.

An inlet valve unit 20 is rigidly secured to the horizontal leg of the rear bracket 11 and in the form of the invention shown, is provided with a pair of inlet nozzles 21 directed toward the interior of the receptacle, a control handle 22 being provided for regulating the flow of water into the receptacle. As will be seen from Fig. 4, the valve unit 20 extends through the bracket 11 and is connected on the under side of the bracket to a source of water supply (not shown) by means of a suitable flexible connection 23, located internally beneath the deck of the fountain.

Adjacent the front wall 5 and preferably in one corner of the receptacle, I provide an over-

flow outlet tube 24 which is supported vertically in a suitable opening in the bottom 9 where it is connected by a coupling 25 and flexible connection 26 to the drainage system of the fountain (not shown). The flexible connection 26 may, if desired, be extended through a transverse opening 27 in the end wall 7 as shown in Fig. 3.

In order to segregate dippers and spoons of different sizes, for example, five-cent scoops, and ten-cent scoops, I provide a vertical, perforated partition 28 which extends longitudinally across the interior of the receptacle and is removably secured in place by bayonet connections 29 or other fastening means fixed to the end walls 7 and 8. In addition to the series of perforations 10 in the partition 28, I may provide an enlarged central opening 30 which serves the dual purpose of facilitating the flow of water through the partition and acting as a finger hole when removing the partition for cleaning.

In the use of my improved fountain receptacle, the device is inserted in a conventional fountain well with the brackets 10 and 11 resting upon the deck of the receptacle adjacent the upper extremity of the well. The forward bracket 10, as before stated, is adjustable vertically to compensate for variations in the angle of inclination of the deck of the fountain, the bracket being clamped in its proper position by the nut and screw assemblies 15.

When it is desired to remove the receptacle for purposes of cleaning and sterilization, the screws 19 in the rear wall 6 of the receptacle, are loosened, permitting the rear bracket 11, together with the valve unit 20, and flexible connection 23, to be lifted from the wall 6. The receptacle is then bodily lifted from the well of the fountain and the coupling 25 removed from the overflow pipe 24. The partition 28 may be removed by disengaging the bayonet connections 29 and sliding the partition out. After cleansing, the device is returned to the fountain well by the reverse procedure.

It will thus be seen that I have provided a very convenient and practical receptacle which may be readily connected and disconnected and which may be used with various conventional soda fountains to greatly facilitate the handling of dippers and spoons.

From the foregoing, it is believed that my invention may be readily understood by those skilled in the art without further description, it being borne in mind that numerous changes may be made in the details of structure without departing from the spirit of the invention as set forth in the following claims.

I claim:

1. A fountain receptacle comprising an open body, horizontally disposed angle brackets for suspending said body in a fountain well having a drain, means for vertically adjusting at least one of said brackets to compensate for variations in the angle of inclination of the fountain deck, a water inlet valve unit removably secured to said body, an overflow outlet, and flexible connections respectively, between said valve unit and a source of water supply and between said outlet and the fountain drain.

2. A receptacle as claimed in claim 1, wherein said inlet valve unit is carried by one of said brackets, and means for removably mounting said bracket on said body.

3. A receptacle as claimed in claim 1, wherein said adjustable bracket is slidably mounted adjacent a wall of said receptacle in a pair of oppositely disposed angle guides, and means for locking said bracket in adjusted position.

4. A fountain receptacle comprising an open body having a bottom, two side walls and two end walls, angle brackets carried by said side walls for suspending said receptacle in a fountain well having a drain, one of said brackets carrying a water inlet valve unit and being detachably connected to the adjacent side wall, the opposite angle bracket being vertically adjustable on its respective side wall to compensate for variations in the angle of inclination of the fountain deck, an overflow outlet pipe supported by and extending through said bottom, flexible connections respectively between said valve unit and a source of water supply and between said outlet pipe and the fountain drain.

5. A fountain receptacle comprising an open body having a bottom, two side walls and two end walls, angle brackets carried by said side walls for suspending said receptacle in a fountain well having a drain, one of said brackets carrying a water inlet valve unit and being detachably connected to the adjacent side wall, the opposite angle bracket being vertically adjustable on its respective side wall to compensate for variations in the angle of inclination of the fountain deck, an overflow outlet pipe supported by and extending through said bottom, flexible connections respectively, between said valve unit and a source of water supply and between said outlet pipe and the fountain drain, and an apertured vertical partition dividing said receptacle into two sections.

6. A receptacle as claimed in claim 5, including means for removably supporting said partition.

7. A utensil cleansing receptacle for use in connection with a soda fountain syrup rail equipped with a source of water supply and a drain, said receptacle comprising an open body, outwardly flanged horizontal supports adapted to engage the edges of a syrup rail for freely suspending said receptacle therein, a water inlet valve unit fixed to and extending through one of said horizontal supports and removable from said syrup rail with said receptacle, a flexible conduit connected to said valve unit on the underside of said support and extending downwardly along the outside of said receptacle to said source of water supply, an overflow tube in said receptacle extending through the bottom thereof, and a flexible conduit connected between said overflow tube and the fountain drain, whereby said receptacle may be bodily lifted from the syrup rail without first disconnecting the water supply and drain.
